The ornamental design for a recessed fluorescent lighting fixture, as shown and described.

DESCRIPTION

FIG. 1 is a perspective view of a recessed fluorescent lighting fixture showing my new design;

FIG. 2 is a bottom plan view of the recessed fluorescent lighting fixture shown in FIG. 1;

FIG. 3 is a top plan view of the recessed fluorescent lighting fixture shown in FIG. 1;

FIG. 4 is a front elevational view of the recessed fluorescent lighting fixture shown in FIG. 1, the rear being a mirror image;

FIG. 5 is a side elevational view of the recessed fluorescent lighting fixture shown in FIG. 1, the opposite being a mirror image; and,

FIG. 6 is an enlarged cross-sectional view of the recessed fluorescent lighting fixture shown in FIG. 1.

FIG. 2

FIG. 5

FIG. 6
